UNITED STATES PATENT OFFICE.

HENRY KREISINGER, OF PITTSBURGH, PENNSYLVANIA, JOHN ANDERSON, OF MILWAUKEE, WISCONSIN, AND JOHN E. BELL, OF BROOKLYN, NEW YORK, ASSIGNEES TO COMBUSTION ENGINEERING CORPORATION, A CORPORATION OF NEW YORK.

METHOD OF AND APPARATUS FOR BURNING PULVERIZED FUEL.

Application filed December 30, 1920. Serial No. 433,991.

To all whom it may concern:

Be it known that we, HENRY KREISINGER, JOHN ANDERSON, and JOHN E. BELL, all citizens of the United States, respectively residing at Pittsburgh, county of Allegheny, and State of Pennsylvania; at Milwaukee, county of Milwaukee, and State of Wisconsin; and at Brooklyn, county of Kings, and State of New York, have invented certain new and useful Improvements in Methods of and Apparatus for Burning Pulverized Fuel, of which the following is a specification.

This invention relates to a method of and apparatus for burning pulverized fuel and it has for one of its principal objects the provision of improvements whereby it is possible to increase, in a furnace of given size, the space utilizable for combustion purposes. Another of the objects is to increase the combustion rate and make it possible to burn more coal in a furnace of given size.

Still another object is to control the direction of flame travel in such manner that a furnace deep but comparatively narrow in its horizontal dimension along the line of the boiler tubes may be used with efficiency. This is of great advantage since the practical limitations of modern boiler-house design are such that but little or no space in front of the boilers is available for extension to increase furnace volume, while there is considerable space available vertically due to the fact that the boilers are set high relative to the floor line and are provided with ample ash-pits beneath the floor, which latter space, in pulverized fuel burning, may be added to the ordinary furnace space.

Our invention also contemplates the provision of improvements whereby natural draft is utilized to the fullest possible extent and the amount of compressed air incidentally required reduced to a minimum so as to increase efficiency by eliminating the power requirements for forced draft and reducing the power requirements for compressed air.

Another object of our invention resides in the provision of improvements by means of

which coarse coal and also wet coal may be burnt successfully whereby the expense of pulverizing is cut down, in the one instance, and the expense of drying machinery avoided, in the other instance.

More specifically, our invention contemplates the provision of improved burner mechanism for pulverized fuel burning furnaces, especially such as are used for generating steam, by means of which the fuel is admitted and burned in a thin, wide, sheet-like stream, approximately continuous across the combustion chamber, such burner mechanism being used in combination with a vertically prismoidal furnace, and air for combustion being supplied in such manner as to secure objects and advantages herein set forth. Our invention additionally relates to the delivery of the fuel, or a mixture of fuel and air, and of additional air in such proportions and at such relative velocities as to secure maximum efficiency in combustion.

The foregoing, together with such other objects and advantages as may hereinafter appear or are incident to our invention, we obtain by a method and apparatus disclosed in preferred form in the accompanying drawings, wherein:

Figure 1 is a longitudinal section through a water tube boiler furnace illustrating our improvements; Figure 2 is a front elevation of the furnace; Figure 3 is a longitudinal section through one of the burners employed in carrying out our invention, drawn on an enlarged scale; Figure 4 is a section of the burner taken on the line 4-4 of Figure 3; Figure 5 is a section on the line 5-5 of Figure 3.

Referring now to Figures 1 and 2, the furnace, indicated as a whole by the reference letter A, comprises the combustion chamber B, which is preferably vertically prismoidal and has an outlet 7 in the upper part or region thereof, preferably in the top; the boiler C, in this instance of the water tube type, set so as to extend over the outlet 7 for the products of combustion; and the burners D which are preferably mounted

so as to deliver the fuel or a mixture of the fuel and air vertically downward into the combustion zone of the chamber B through the top wall 8. Ash doors 9 are provided in 5 the bottom of the front wall 10 of the chamber. The furnace preferably has a natural draft created by a stack (not shown).

There are a plurality of the burners D, preferably spaced equidistant in a row ex-

10 tending across the furnace and located so as to deliver the fuel near the front wall 10 to subject the fuel to its radiant heat. Each burner consists of a casting 11, somewhat like an elbow, in which depends a burner nozzle 12 and the member 13 hung on the upper part of the casting 11 which is suitably apertured to permit of the introduction of the burner parts. The nozzle 12 is flared out from the 15 top toward the bottom, from a somewhat oval to a flat cross section, the opening 12^a in the lower portion being wide in one dimension and narrow in the other. The opening in the member 13 changes from a circular 20 to an oval section. The burner may therefore be described as of a "fish tail" type. A delivery pipe 14 is connected with each of the members 13. The burner nozzle 12 terminates above the lower end of the casting, 25 so that the stream of fuel, which is discharged therefrom in the form of a thin, wide sheet approximately parallel the front wall of the combustion chamber, may be surrounded by air as will now be described.

30 Located within the casting 11 is a vertical wall or septum 15, such wall being on that side of the nozzle nearest the boiler. The upper end of the wall 15 is preferably somewhat below the inlet 16 of the casting, while 35 the lower portion of the wall terminates short of the lower end of the casting. The interior of the casting is thus divided into two chambers *a* and *b* communicating with the space *c* at the top. The burner nozzle 40 thus extends into chamber *b*, and to control the air supplied to such chamber we provide a pair of dampers 17 cut out so as to fit around the burner nozzle and operated by the worms 18 and segments 19. By manipulation of such dampers the amount of air supplied to chamber *b* around the nozzle and therefore around the fuel stream may be 45 regulated for a purpose which will appear. This in turn effects somewhat of a regulation of the air passing through chamber *a*. Another damper 17^a controls the inlet to the 50 space *c* of the casting. Thus the air supplied at the draft side of the fuel delivery nozzle 12 can be separately regulated (in a practical sense), since it can be varied both 55 in absolute amount and relatively to any air supplied at the other side of the nozzle and the fuel stream.

60 Additional air for combustion is also supplied through the front wall of the combus-

tion chamber at a plurality of points, as by means of the damper controlled inlets 20. The air thus admitted at 20 serves to cool and protect the front wall, and to afford a cooling zone in the bottom of the chamber B 70 beneath the combustion zone, for preventing fusing together of the falling particles of ash or slag,—as is well understood in this art.

The operation is as follows, assuming that 75 the furnace is hot enough to maintain ignition:

The burners deliver a mixture of fuel and air to be hereinafter described in a series of juxtaposed thin sheet-like streams which 80 are surrounded by induced air and which almost immediately unite to form a substantially continuous sheet across the width of the combustion chamber. This ignites, and the flame is spread across the combustion 85 chamber so that the surface in contact with the air and the surface exposed to the radiant heat of the furnace and for initial combustion is a maximum for the furnace width. As a result, the rate of combustion is increased and it is possible to burn more coal in a furnace of given size and also to ignite and burn readily coarser coal than heretofore. The stream of fuel and flame is turned upwardly by the draft so that it takes a substantially U-shaped course in the combustion chamber, the combustion being practically completed therein and the products of combustion then passing amongst the boiler tubes.

100 Since the fuel and flame stream, particularly the descending part thereof, is in the form of a sheet extending across the combustion chamber, it is advantageous to supply some of the additional air needed for combustion on the exterior of the fuel sheet through the openings 20, and other quantities in the interior, that is between the descending and ascending portions of the fuel and flame stream. This latter is accomplished by the chambers *a* through which streams of air are induced by the furnace draft, adjacent the incoming fuel and air. This additional air thus does not have to 105 pass through the stream of fuel and flame and does not therefore break up the stream lines. All the air required is supplied substantially above the bottom of the chamber, so that an effective cooling zone can be established in its lower region, even with considerable variation of flame level.

110 Another and very important advantage of this arrangement is that the depth of the flame travel, i. e. the level of the base of the flame may be altered as desired, and the 115 flame may be caused to sweep down well toward the bottom of the combustion chamber, thereby increasing the volume of space utilizable for combustion purposes. To drive the flame downward and thus lower the 120

100

105

110

115

120

130

"flame level" (so to term it) in the combustion chamber B, it is only necessary to increase the downward momentum of the incoming air supply on the inside of the flame 5 by closing dampers 17-17 and opening damper 17^a to the extent required. The consequent increase in the length of travel of the flame, and its extent away from its point of admission increases the space in the furnace 10 actively used and made available for combustion. This is diagrammatically indicated in dotted lines in Figure 1. Again if the flame impinges on the furnace floor the damper 17^a is partially closed and the 15 dampers 17 opened. Or these same results may be accomplished by manipulating the furnace draft and dampers 17 leaving damper 17^a in a fixed position.

Further, it will be seen that by delivery 20 and burning of the fuel in a thin sheet, the descending and ascending portions of the fuel and flame stream can be brought more closely together, and when this is coupled with the fact that the stream can be made to 25 turn approximately at any desired level, it will be observed that it is possible to efficiently burn pulverized fuel, in a furnace which is deep but narrow in horizontal width in the line of the boiler tubes, that is 30 to say in a furnace in which volume is secured by depth more than by width. Thus pulverized fuel equipment may be effectively installed without exceeding the limitations imposed by standard boiler-house 35 design.

It will also be observed that the ability to bring the descending and ascending portions of the fuel and flame stream more closely together promotes more effective and more 40 rapid combustion because the former portion is more intimately subjected to the heat of the latter portion, this being particularly advantageous in the burning of anthracite coal. The effectiveness of this feature will 45 be better appreciated when it is considered that the length of the descending and ascending portions of the stream may be increased.

We prefer to admit the mixture of fuel 50 and air at a velocity such that, in the absence of the additional air, the flame will not reach the bottom portion of the furnace, and then to induce the additional air by the draft and regulate the air supply in the manner indicated so as to lower the flame to the 55 desired level, the additional air being supplied at less velocity so as to produce an eddy action adapted to bring fresh supplies of air in contact with the fuel and flame. 60 To be more specific, the additional air admitted around the fuel stream and the air admitted on the inside of the fuel and flame stream is supplied at less velocity so that 65 eddies will be produced by the difference in relative velocities. The air admitted

through the openings 20 is also at lower velocity so that it will tend to follow and border the stream lines of the fuel and flame and provide a body of air into which the heavier particles of fuel not consumed or 70 only partially consumed will gravitate and be burned.

The method and apparatus are such that it is unnecessary to provide forced draft, the natural draft being adequate to secure maximum efficiency. Thus there is a minimum 75 interference with natural stream lines, blow torch action is eliminated and at no time is there an impingement of sufficient force to cause running or flowing of the refractories.

Furthermore, we have found that by our process and apparatus it is necessary to supply only a small proportion of the air required for combustion with the fuel delivered to the burners, say for example 10% 80 or less, and this air should be supplied at a low pressure, just sufficient for it to act as a carrier. Thus, the usual power requirements for the forced draft are eliminated, and the incidental requirements for fuel carrying air are reduced to a minimum, the total saving over stroker practice being sufficiently great to pay for the cost of pulverizing.

In this latter connection, it is to be observed that the shape of the burner is such as to break up the particles of coal which stick together when the coal is not dried, this together with the large surface exposed making it possible, if desired, to burn coal 90 having a higher percentage of moisture than usual, the final combustion of such coal being secured by the other advantages incident to our invention and heretofore noted.

We claim:

1. The method of burning pulverized fuel in suspension in a furnace having an outlet in an upper part thereof, which consists in introducing and igniting the fuel in a downwardly directed stream so that the fuel and flame stream must take a U-shaped course through the combustion chamber to said outlet, in admitting parallel to said stream and in juxtaposition thereto on each side thereof a stream of combustion-supporting air, 105 and in inducing, under the influence of the natural draft of the furnace, a separately regulable, downwardly directed, stream of air, of less velocity than the fuel and flame stream, adjacent the first-mentioned stream 110 of air and between the descending and ascending legs of the U, to control the level at which said fuel and flame stream turns upwardly.

2. In combination with a pulverized fuel 125 burning furnace having an outlet in an upper part, a burner, positioned to admit the fuel downwardly, and comprising a casing, having an upper receiving portion and a lower discharge portion, a septum positioned 130

longitudinally of said casing and dividing the discharge portion thereof into two passages, one of which is between the furnace outlet and the other passage, a fuel nozzle, 5 greater in one cross-sectional dimension than in the other, extending through the upper receiving portion of said casing and into the passage most remote from the furnace outlet, 10 an air inlet in the casing adapted to admit air into both of said passages, a damper for said inlet, and separately regulable dampers

one on each side of the fuel nozzle in the passage into which the nozzle extends.

In testimony whereof I have hereunto signed my name.

HENRY KREISINGER.

In testimony whereof I have hereunto signed my name.

JOHN ANDERSON.

In testimony whereof I have hereunto signed my name.

JOHN E. BELL.
